UNITED STATES PATENT OFFICE.

JACOB WALLACE, OF PLYMOUTH, OHIO.

AUTOMATIC FEEDER AND EXERCISER.

1,048,771.

Specification of Letters Patent.

Patented Dec. 31, 1912.

Application filed June 12, 1911. Serial No. 632,812.

To all whom it may concern:

Be it known that I, JACOB WALLACE, a citizen of the United States of America, residing at Plymouth, in the county of Rich-
5 land and State of Ohio, have invented cer-
tain new and useful Improvements in Au-
tomatic Feeders and Exercisers, of which
the following is a specification.

This invention relates to certain new and
10 useful improvements in poultry feeders, and
the object of the invention is to provide an
improved simple and effective type of means
for feeding the grain.

Further and other objects will later ap-
15 pear.

In the drawings: Figure 1 is a vertical
sectional view of the present invention, Fig.
2 is a top plan view showing the cover re-
moved, Fig. 3 is a bottom plan view of the
20 feed disk, and Fig. 4 is a sectional view of
Fig. 3. Fig. 5 is a cross section taken
through the baiting device.

In the embodiment of the invention a
hopper 1 is employed having a funnel-
25 shaped bottom portion 2 which terminates
in a flat bottom proper 3 which is formed
with a central comparatively large opening
4. The top of the hopper is closed by a
cover which includes a cone-shaped portion
30 5 to which a depending rim 6 is riveted, the
latter being received on the interior of the
hopper 1, the hopper having its upper or
free end curled outwardly as at 7 to form
an abutment engaging the under face of
35 cone 5 to thereby restrict the inward move-
ment of the cover, and at the same time to
provide a rounded edge which will not cut
the cover.

8 designates a series of legs which are
40 preferably formed of channel iron riveted
to the outer side of the hopper by means of
which the latter is supported above the
ground.

On the interior of the hopper in the cone-
45 shaped portion 2 thereof a horizontal cross
bar 9 is located, the latter having its ends
10 bent upwardly at an angle to the body
of the cross bar and secured by means of
bolts 11 to the cone-shaped part 2. The
50 cross bar 9 is located at a distance above the
bottom proper 3 and is provided with a
central perforation through which the up-
per end of the vertical rod 12 extends. By
reference to Fig. 1 it will be observed that
55 the opening 13 through which the upper
end of rod 12 extends is of greater diameter

than the latter in order to not only permit
the rod 12 to rotate with respect to the cross
bar 9, but in addition to permit the same
to have an oscillatory movement, that is to
say the rod 12 is capable of being swung in
any direction out of the vertical toward
and away from the legs 8. The ends of the
rod 12 are threaded and the upper end
thereof is provided with a nut 14 and a lock
nut thereabove designated 15, the nut 14
engaging on the top face of cross bar 9 by
virtue of which engagement the rod 12 is
suspended in an obvious manner.

A flat feed disk 16 is mounted on the up-
per end of rod 12 in the space between the
bottom 3 and cross bar 9 and is held on
said rod in adjustable position by means of
nuts 17 and 18 the latter engaging on oppo-
site sides of the disks 16 and hold the same
rigid with respect to the rod 12. It will be
observed that by proper manipulation of
the nuts 17 and 18 that the disk 16 may be
adjusted to move the same toward or away
from the opening 4 in order to regulate the
feed of the grain, permitting the latter to
egress through opening 4 in regulable quan-
tities.

On the under face of the disk 16 and
preferably cast integral therewith are a se-
ries of blades 19, the latter being of ap-
proximate V-shape and being disposed ra-
dially with respect to the center of the disk
in spaced relation so as to provide a plu-
rality of feed passages 20, in such spaces
between the blades 19. The blades 19 ter-
minate at the periphery of the disk 16. It
will be seen that the blades 19 provides a
series of agitators the pointed lower ends
of which in the oscillatory movement of the
latter will dig into the grain so to speak and
move the same toward the feed outlet 4.
This is a desideratum inasmuch as the rod
12 is given an oscillatory movement oftener
by the poultry than a rotatable one.

100 A cone-shaped deflector 22 is formed at
its apex on the interior thereof with an
enlarged portion 23 provided with a thread-
ed perforation through which rod 12 passes
and by virtue of which the deflector may be
105 moved toward and away from feed outlet 4.

24 designates a horizontally disposed bar
which is formed with a perforation through
which the lower end of rod 12 passes, nuts
25 and 26 engaging the bar 24 on opposite
sides thereof. The bar 24 is preferably
formed in two sections as shown in Fig. 2,

the bar 24 being of equilateral triangular cross section. A sheet of rubber 27 is placed over the sides of the bar 24 and is secured thereto by virtue of a series of rivets 28 the 5 latter passing through the two sections of bar 24 and serve to not only secure the latter together but in addition secure the rubber sheet 27 in position. The rubber sheets 27 are utilized for the purpose of allowing the 10 poultry to peck at the same.

What is claimed is:

1. In a poultry feeder in combination with a hopper having a central feed outlet in its bottom, a cross bar in the hopper arranged above the bottom thereof, said cross bar having an opening, a rod having a baiting device at its lower end and having its upper end passed through the opening of the cross bar, said opening of the cross bar 15 being of greater diameter than the diameter of the rod to permit the latter to have an oscillatory movement in addition to a rotary movement with respect to the cross bar, a flat feed disk secured to the rod above the 20 hopper bottom and below said cross-bar and being formed on its under face with a series of spaced V-shaped blades which point downwardly toward the hopper bottom, so that when the rod is oscillated said blades 25 will dig into the feed and move the same toward the feed outlet during the oscillation 30 of the rod.
2. In a poultry feeder in combination with a hopper, having a feed outlet in its bottom, a rod extending through the outlet and carrying a baiting device on its lower end, means for mounting the rod at its 35

upper end so that the same has an oscillatory movement, a feed disk carried by the rod and located above the hopper bottom, 40 and a series of radial blades carried by the under face of the feed disk for moving the feed toward the feed outlet on oscillations of the rod.

3. In a poultry feeder, a hopper having a 45 funnel shaped bottom portion which terminates in a flat bottom proper having a comparatively large opening, a horizontal cross bar having its ends secured to the funnel shaped bottom portion above the bottom 50 proper, a rod having a baiting device on its lower end and having its upper end threaded and loosely extending through the opening of the bottom proper, the cross bar having an opening of greater diameter than 55 that of the rod through which the threaded end of the latter loosely passes, a flat feed disk adjustably mounted on the threaded end of the rods and disposed between the cross bar and the bottom proper of the 60 hopper, a series of downwardly projecting pointed elements carried on the under face of the disk and having their points surrounding the opening in the bottom proper of the hopper, and means on the extreme 65 upper end of the rod to engage on the cross bar to support the rod against downward movement.

In testimony whereof I affix my signature in presence of two witnesses:

JACOB WALLACE.
